CLAIM

We claim the ornamental design for a in-line signal processor, as shown and described.

DESCRIPTION

FIG. 1 is a perspective view thereof;

FIG. 2 is a top view thereof;

FIG. 3 is a bottom view thereof;

FIG. 4 is a side view thereof;

FIG. 5 is a reverse side view thereof;

FIG. 6 is a front view thereof; and,

FIG. 7 is a end view thereof.

The broken lines form no part of the claimed design.
